DESIGN FOR A DISPLAY CONTAINER

Gustav Jensen, New York, N. Y., assignor to
Bulova Watch Company, Incorporated, New
York, N. Y., a corporation of New York

Application August 12, 1941, Serial No. 102,804

Term of patent 14 years

To all whom it may concern:

Be it known that I, Gustav Jensen, a citizen of the United States, residing in the city, county, and State of New York, have invented a new, original, and ornamental Design for a Display Container, of which the following is a specification, reference being had to the accompanying drawing, forming part thereof.

Figure 1 is a perspective view of a display container as seen from the front thereof showing my new design;

Figure 2 is a perspective view of the display container of Figure 1 as seen from the back thereof; and

Figure 3 is a perspective view of the display container of Figure 1 showing the cover thereof in its open position, the view being from the front of the container.

I claim:

The ornamental design for a display container, substantially as shown and described.

GUSTAV JENSEN.
